Atty.

UNITED STATES PATENT OFFICE.

FORREST G. PURINTON, OF WATERBURY, CONNECTICUT, ASSIGNOR TO THE PATENT
BUTTON COMPANY, OF WATERBURY, CONNECTICUT, A CORPORATION OF CON-
NECTICUT.

BUTTON.

Application filed October 22, 1924. Serial No. 745,153.

To all whom it may concern:

Be it known that I, FORREST G. PURINTON, a citizen of the United States of America, residing at Waterbury, in the county of New Haven and State of Connecticut, have invented certain new and useful Improvements in Buttons, of which the following is a specification.

My invention relates to new and useful improvements in buttons and more particularly to a button that is made of metal such as aluminum or zinc, and in its broadest aspect is of the same general type as the button shown in a previous application filed by me in the United States Patent Office on April 11, 1923, and bearing Serial Number 631,254.

One of the objects of the present invention is to provide a button of the character described which will be neat and attractive in appearance, rugged in construction and so designed that it may be manufactured in large quantities at an exceedingly low cost.

I have found that it is desirable to so arrange the eye shank that it will assume a definite position when being fed through the automatic machine, and will assume also a definite position when being inserted in the head or body of the button. In the present invention this is obtained by first securing the eye shank to a disc or shell or what might be termed a sub-base, the sub-base not only providing a more rigid construction when the button is assembled, but also holding the eye shank in the desired position as the plunger of the machine wedges the metal of the button about the base.

In the former application above referred to, it was necessary for the swedging tool to engage the eye and should the eye be slightly out of alignment, the anchorage might not be all that is desired. By the present arrangement, however, the tool that is used to force the aluminum or zinc of the button over the edge of the shell or sub-base, may have a clearance hole in the middle thereof large enough to readily clear the sides of the wire eye, thus allowing more lee way in the accommodation of the eye to the swedging tool.

With these and other objects in view, the invention consists in certain new and novel constructions and combination of parts as

will be hereinafter more fully described and pointed out in the drawings.

55

Referring now more particularly to the drawings, showing a preferred embodiment of the invention,

Fig. 1 is a sectional view of a button showing the sub-base and eyelet, as well as the head.

Fig. 2 is a similar view with the parts assembled.

Fig. 3 is also a similar view, and showing the metal of the head swedged about the sub-base.

Fig. 4 is a perspective of the button,

Fig. 5 is a bottom plan view.

Fig. 6 is a sectional view of a slightly modified form, and

79

Fig. 7 is a similar view of a still further modification.

Referring now to the preferred form, the head 1 of the button is formed somewhat similarly to that shown in my former construction, wherein a rod or wire (not shown) is cut to from a slug, or rod-like blank and then subjected to suitable dies in a heading machine, and pressed to the desired shape, as shown in Fig. 1. It will be seen that this head is preferably curvi-form as at 2, a central hub 3 being provided which is recessed or hollowed out as at 4, the rim extending outwardly as at 5, and merging with the hub as at 6. By pressing the button head into this shape, the upper portion of the hub is in the form of a rim which is to be swedged, as will be shortly described.

It will be understood that the top of the button might be a plane surface rather than that as shown, but the slightly curved outer face presents a near and pleasing form of button.

Referring now to what I term the sub-base 7, it will be seen that it consists of a metal shell or disc substantially hemispherically in shape, while forced centrally through the top thereof is the eye shank 8 having its ends bent or crimped against the top of the shell to thus form a tight and rigid construction between these two elements. The diameter of this shell is slightly less than the recessed portion 4 formed in the head of the button so that the sub-base, during its assembly in the machine, may slide or drop within this pocket, the shell meanwhile

supporting the eye shank in its proper position. The depth of the shell is slightly greater than the depth of the recess 4 as will be apparent from the several figures.

5 After the shell has dropped into its position, the metal rim is properly swedged by the plunger (not shown) to tightly anchor the shell in position, as may be clearly seen in Fig. 3.

10 In the modified form, as in Fig. 6, a soft metal head 9 is shown in which there is formed a slight central aperture 10 and placed therein is the shell or sub-base 11, in which there has been formerly secured the 15 eye shank 12. The metal around the aperture 10 will then be swedged inwardly to tightly grasp or anchor the shell 11 and its eye 12, in position.

In a like manner, the modified form 20 shown in Fig. 7 illustrates a button head 13 of soft metal and instead of having a central aperture or cut-out portion in which the sub-base fits, there is shown an annular groove, recess or depression 14 in which will fit 25 the edge of the shell or sub-base, the latter of course provided with the eye shank 16. In this form also, the metal about the edge of the recess or groove will be swedged inwardly to tightly anchor a shell or sub-base 30 15 within the button head.

From the foregoing it will be seen that I have provided a button wherein the head is preferably made of soft metal which permits advertising or other insignia to be 35 pressed on the face thereof, and at the same time provides a button that is neat in appearance and easily assembled. Furthermore, the preliminary attaching of the eye

shank to the sub-base or shell not only makes it possible to make a rigid form of button, 40 but allows the button to be made at a maximum speed inasmuch as the plunger may work on the shell with the eye shank in its proper position rather than have the plunger descend upon a shank that is not in its 45 proper position.

I am aware that it is old in the art to provide a soft metal button and to swedge the same about the lower ends of the eye shank, and do not claim this invention 50 broadly as shown, but what I do claim and desire to secure by Letters Patent is:—

A button comprising a metal head, said head provided with a central hub of greater thickness than the mean thickness of the 55 head, said hub having a recess portion thus providing an upstanding rim, a sub-base formed of a metal disc, cup-shaped in cross section and its exposed surface being curved throughout, said sub-base being fitted within the recess portion and the peripheral edge of its downwardly extending walls contacting with the bottom of the said recess portion, an eyelet secured in said sub-base and the metal rim swedged to anchor the said 60 base within said button and the rim when swedged extending in a plane above the surface of the button and substantially in the same plane as the curved upper surface of the sub-base, the swedged rim and the upper 65 surface of the sub-base providing a space between the button head and the material to which it is to be fastened.

In testimony whereof I affix my signature.

FORREST G. PURINTON.
